SECONDARY RECOVERY BY MISCELLY FLUID
DISPLACEMENT

Benzion Habermann, Montebello, Calif., assignor to
Union Oil Company of California, Los Angeles, Calif.,
a corporation of California

Filed July 6, 1959, Ser. No. 825,128
5 Claims. (Cl. 166—9)

This invention relates to secondary recovery of petroleum from subterranean reservoirs. Specifically, it relates to a miscible fluid displacement method of secondary recovery with an improved areal sweep efficiency.

In attempts to recover petroleum from subterranean reservoirs in addition to that recovered by primary techniques, much attention has recently been focused on the miscible fluid slug displacement method of secondary recovery. In this method, a fluid miscible with both the crude petroleum and a drive fluid is injected into the formation from an injection well and is forced through the formation to drive or carry the crude petroleum towards a suitably located production well. Examples of miscible fluids which have been so employed are L.P.G., propane, butane, pentane, and petroleum distillates. Since such fluids are relatively expensive they are in turn forced through the formation by a less expensive driving fluid, e.g., natural gas, methane, ethane and mixtures of natural gas and water. The miscible fluid is then employed in the form of a slug interposed between the driving fluid and the crude petroleum, and is provided only in an amount sufficient to insure separation of the driving fluid and the petroleum.

Although miscible fluid displacement provides high oil recovery from the swept area, much difficulty has been experienced in obtaining a satisfactory areal sweep of the displacing fluids. The poor areal sweep of the miscible fluid slug has been found to be related to the unfavorable mobility ratio between the miscible fluid and the oil. The mobility ratio is determined by the following equation:

$$M = \frac{K_2}{K_1} = \frac{\mu_1}{\mu_2} \times \frac{K_2}{K_1}$$

where

M =mobility ratio;

μ_2 , μ_1 =viscosity of displacing fluid and displaced fluid, respectively;

K_2 , K_1 =permeability of the formation with respect to the displacing fluid and displaced fluid, respectively.

The areal sweep efficiency is indirectly proportional to the mobility ratio, and, as the above equation shows, the latter is directly proportional to the ratio of displaced fluid viscosity to displacing fluid viscosity and directly proportional to the ratio of displacing fluid permeability to displaced fluid permeability.

In most miscible fluid displacement operations, the permeability ratio, K_2/K_1 , is more or less fixed by the inherent characteristics of the formation. Thus, the viscosity ratio, μ_1/μ_2 , is the controlling variable in the mobility ratio, and becomes the determining factor in the areal sweep efficiency of a miscible fluid displacement.

2

Any reduction of the viscosity ratio, particularly if such ratio is normally greater than 1, will result in a better areal sweep, provided the miscibility of the fluids is not disturbed. Previous attempts to improve the sweep efficiency have centered around attempts to adjust either the miscible fluid viscosity, only, or to adjust the mobility ratio between the drive and miscible fluid phases, only, without compensating for an adverse permeability ratio, and without regard to the adverse effect such adjustments may have on the miscibility of the drive fluid with the miscible fluid. The reported studies on this problem have also been conducted at relatively low mobility ratios between the drive and the oil phases and, therefore, are not indicative of actual reservoir conditions where unfavorable mobility ratios of the order of 30 to 80 are frequently encountered.

This invention is directed to improving the areal sweep efficiency of a miscible fluid displacement under reservoir conditions. It is the purpose of this invention to attain favorable mobility ratios between the drive fluid, the displacement fluid and the reservoir oil while retaining miscibility of the fluids. In reservoirs which have a low permeability with respect to the connate oil due to free gas saturation, it is also within the scope of this invention to compensate for the adverse permeability ratio of oil to miscible fluid by increasing the miscible fluid viscosity to a greater value than the oil viscosity, thereby obtaining the most favorable mobility ratio. It is also a purpose of this invention to retain high solubility of the miscible displacement fluid for the driving fluid. Another aspect of this invention is a method to plug fingers and flow channels in a formation by depositing a polymer in the fingers.

These purposes are achieved in accordance with this invention by the addition of a long chain polymer to the miscible displacement fluid. Small amounts of a long chain polymer dissolved in a light hydrocarbon cause a substantial increase in viscosity of the solution. The presence of the polymer has little effect on the solvent properties of the displacement slug, and the miscibility of the latter with both the crude oil and the driving fluid is relatively unaffected. Under these conditions, high areal sweep efficiencies can be attained. Drive fluids employed are methane, ethane and natural gas, alone, or mixed with water. In a preferred modification, the viscosity of the drive fluid is adjusted to provide a low mobility ratio between the drive and the miscible fluids. This may be achieved by use of a mixed water-gas drive, by simultaneous injection of gas and water, or gas and an aqueous polymer solution. During displacement, the reservoir is kept under sufficient pressure to keep the miscible fluid in a liquid state but not under a pressure sufficient to cause fracturing, i.e., less than about 3,000 p.s.i.

The invention will be described in greater detail hereafter and illustrated by the figures of which:

FIGURE 1 illustrates the viscosity of hydrocarbon solutions of long-chain polymers;

FIGURE 2 illustrates a section of a producing field in which the invention can be practiced;

FIGURE 3 illustrates the amount of oil recoverable as a function of the mobility ratio in a typical oil displacement process;

FIGURES 4 and 5 illustrate the areal flow pattern in the displacement described in Example 1;

FIGURES 6 and 7 illustrate the areal flow pattern of the displacement process described in Example 2;

FIGURES 8 and 9 illustrate the areal flow pattern for the displacement process described in Example 3;

FIGURES 10 and 11 illustrate the areal flow pattern obtained in Example 4 when using a displacement process in accordance with my invention;

FIGURE 12 illustrates the miscibilities of the reservoir oil, displacement medium and drive gas;

FIGURE 13 illustrates the gradation in viscosity of a plurality of viscous displacing fluids; and

FIGURE 14 illustrates the process steps of one embodiment of my invention whereby increased recovery of reservoir oil is attainable.

The increase in viscosity effect noted with solutions of long chain polymers is related to the molecular weight and shape of the polymer chain. The relationship between viscosity and molecular weight is as follows:

$$[n] = KM^a$$

where

K and a are constants for a given series of polymers; M equals the polymer molecular weight;

[n] is the intrinsic viscosity and is obtained by extrapolating to zero concentration a plot of:

$$\frac{1}{C} \left[\frac{n - n_0}{n_0} \right]$$

versus concentration, where

C=concentration;

n=viscosity of solution;

n_0 =viscosity of solvent.

The values of K and a are reported in available literature on polymers, e.g., Synthetic Rubber, by G. S. Whitby, p. 331.

Any long chain oil-soluble polymer exhibiting a high solution viscosity is appropriate for use in accordance with the invention. Examples of suitable polymers are: polymers of butadiene, isobutylene, chloroprene, copolymers of butadiene and styrene, methacrylate, or acrylonitrile, copolymers of isobutylene and isoprene, natural rubber, and polyvinyl chloride plasticized with tricresyl phosphate. The above formulas show that the increase in viscosity of a polymer solution is a direct function of the polymer molecular weight. Expressed in another form, the formulas show that the greater the polymer molecular weight, the lower the concentration of the polymer needed to achieve any given solution viscosity. The maximum molecular weight of polymers useful in this invention is limited only by the solubility of the polymer in the miscible displacement fluid. Although the lower molecular weight polymers are more soluble, their use is disadvantageous since relatively large quantities of the polymer must be added to achieve a satisfactory viscosity increase. The preferred polymers are those which effect a substantial increase in the viscosity of the displacement fluid at concentration less than about 1 percent by weight, and which have molecular weights greater than about 10,000 and preferably between about 500,000 and 1,500,000. Sufficient polymer is added to the hydrocarbon liquid to cause more than a 10 percent increase in viscosity. The amount of polymer added varies for each polymer but is generally between 0.01 and 1 percent by weight, and preferably from 0.05 to 0.5 percent by weight. The displacement fluid can be any liquid in which the polymer can be dissolved and which is miscible with the connate oil and the drive fluid. Examples of suitable fluids include petroleum distillates, crude oil, petroleum ether, paraffin hydrocarbons such as butane, pentane, hexane, heptane, L.P.G., aromatics, such as xylene, toluene, benzene, coal tar oils, cyclohexane, or mixtures thereof. Preferred fluids are L.P.G., propane, butane, isobutane, pentane, isopentane, hexane, isohexane, gasoline and kerosene. The optimum combination of polymer

and displacement fluid will, of course, be dictated by reservoir characteristics and economic considerations.

All of the above mentioned polymers and solutions are illustrative only and are not to limit the invention which is operative with any viscous oil-soluble polymer solution which is miscible with both the drive fluid and the reservoir oil. In those cases where the polymer is insoluble or only slightly soluble in the miscible fluid employed, such as polyisobutylene which is not soluble in hydrocarbons lighter than pentane, it is within the scope of this invention to add a second fluid to the miscible fluid as a secondary solvent, hereafter referred to as a solutizer, to increase the polymer solubility. Examples of such solutizers are cyclohexane, decalin, tetralin, pyridine, or any of the above mentioned solvents for the polymer. The following table shows the effect of such solutizers on the solubility of polyisobutylene in isobutane:

TABLE I

Temperature, ° F.	Isobutane, cc.	Cyclo- hexane, cc.	Decalin, cc.	Polyisobutylene Dissolved	
				Grams	Gram/ 100 cc.
25					
75	100	0	0	0.0	0.0
75	83	26	0	0.26	0.24
100	68	26	0	0.26	0.28
75	119	0	23	0.23	0.16
90	119	0	23	0.23	0.16

The effect of polyisobutylene addition on the viscosity of normal heptane is shown in FIGURE 1, which is a plot of viscosity in centipoises of the solution versus weight percent of polyisobutylene in normal heptane. From this graph, it is seen that polyisobutylene in as low a concentration as 0.3 weight percent will more than quadruple the viscosity of normal heptane from a value of 0.4 centipoise to 1.68 centipoises at 100° F. This substantial increase in solution viscosity for low concentrations of polymer is a characteristic of all the above mentioned long chain polymers and is an important factor in practicing the invention since it affords an economical method of increasing the viscosity of an oil-miscible fluid to the degree necessary for use in the secondary recovery of oil. It is of course apparent that other oil-miscible fluids and other solutizers may be used, e.g., L.P.G., as a miscible fluid with added hydrocarbon solutizers such as petroleum distillates or even a portion of the crude oil. The use of a viscous distillate or crude oil as a solutizer has the advantage that the viscosity of the solutizer has an additive effect on the solution viscosity. The choice of any oil-miscible fluid and solutizer will be governed largely by economic conditions and the availability of the components.

As previously mentioned, the driving fluid may comprise an aqueous polymer solution which is injected into the formation simultaneously with a gas such as methane, ethane or reservoir gas. Preferably, the polymer is a water-soluble partially hydrolyzed acrylamide polymer. These partially hydrolyzed acrylamide polymers are water-soluble acrylamide polymers which have been hydrolyzed to such an extent that between about 0.8 and 10 percent of the amide groups have been converted to carboxyl groups. As herein employed, the term "acrylamide polymer" is inclusive of the homopolymers of acrylamide, i.e., polyacrylamide, and water-soluble copolymers of acrylamide with up to about 15 percent by weight of other polymerizable vinyl compounds, such as the alkyl esters of acrylic and methacrylic acids, methacrylamide, styrene, vinyl acetate, acrylonitrile, methacrylonitrile, vinyl alkyl ethers, vinyl chloride, vinylidene chloride, etc. In addition to the aforementioned limitation on the extent of hydrolysis, the acrylamide polymers suitable are of sufficiently high molecular weight that a 0.5 percent by weight aqueous solution thereof has a viscosity of at least

4 centipoises Ostwald at 21.5° C. A commercially available polymer meeting these requirements is marketed by The Dow Chemical Company under the name "Separan." The above mentioned polymers are preferred, since they form a stable solution and do not easily precipitate when heated or when in the presence of mineral anions and cations, however, the use of any other water-soluble material which forms a stable viscous aqueous solution is also within the scope of the present invention; examples of such materials include polyvinyl alcohol, carboxymethyl cellulose, sucrose, etc.

The use of an oil-soluble polymer dissolved in a light hydrocarbon as the miscible fluid slug permits adjustment of the viscosity of the miscible displacement fluid through a range of values from that of the low viscosity light hydrocarbon solvent up to and exceeding the viscosity of the reservoir oil, thereby permitting compensation for adverse permeability ratios. It is also possible to stage the solution viscosity at successively decreasing or increasing values from the miscible fluid-oil interface to the miscible fluid-drive fluid interface without altering the miscibility of the fluids. This permits gradual change from the high viscosity oil to a low viscosity drive without any sharp change in viscosities, thereby avoiding high mobility ratios. Conversely, it is possible to gradually increase the viscosity from a low viscosity oil to a high viscosity drive.

Adverse permeability ratios may be compensated for in accordance with the following discussion. The mobility ratio, M , of the fluids is directly proportional to the ratio of the permeability with respect to the miscible slug, K_s , to the permeability with respect to the connate oil, K_o . Under reservoir conditions, the ratio K_s/K_o is generally greater than one. K_o is frequently relatively low by reason of the presence of free gas saturation of the oil phase occurring when the reservoir pressure is below the bubble point pressure, which is defined as the highest pressure at any given temperature at which gas bubbles will form in the oil phase. This condition can occur naturally or be caused by pressure depletion during primary recovery. K_s , however, is not reduced proportionately since the mixed oil and gas phase is swept out of the formation ahead of the slug. As a consequence, the permeability ratio is adverse, and even though the miscible slug viscosity is increased to equal the oil viscosity, the mobility ratio of the fluids, M , will not be corrected for the adverse permeability ratio. However, by practicing this invention in the use of a polymer additive to the miscible fluid slug, the slug viscosity may exceed the oil viscosity, and the most favorable mobility be achieved by setting the slug viscosity in accordance with the following equation:

$$\mu_s \geq \mu_o \frac{K_s}{K_o}$$

In addition to the above adjustments of mobility ratios possible through use of polymer solutions, another unique procedure may be followed after fingering has occurred and the miscible fluid slug has broken through to the producing well. This procedure is illustrated in FIGURE 14. As illustrated, the aforescribed miscible displacement is continued until breakthrough, steps 1 to 3. Upon breakthrough, step 4, the pressure on the well is reduced, whereby the displacement fluid vaporizes and the dissolved polymer precipitates. During depressurization, there will be a flow of the polymer solutions into the finger or flow channel, concentrating the polymer in this flow channel where it will deposit and seal off the channel. When this has occurred, the reservoir is again pressurized and the miscible fluid drive repeated. The polymer deposited in the fingers of the preceding drive will remain in place, sealing these flow channels, and a new flow pattern will occur with the second drive, thereby increasing the total area swept. This procedure can be improved by use of methods to detect the miscible fluid slug before it reaches the producing well. When proximity of the slug to the

producing well is detected, the formation is depressurized and the polymer deposited in the fingers leading to the producing well, but not immediately adjacent the well and thus the danger of plugging off the well is avoided.

5 Proximity of the miscible fluid slug can be determined by use of an identifiable fluid in front of the miscible fluid slug. Such a fluid can be identified by any easily measured property, such as content of a radioactive tracer, gravity, viscosity, or even color. Gravity and viscosity must be 10 carefully chosen, however, so as not to affect the vertical and horizontal sweep of the miscible fluid slug.

In some instances, it may not be necessary to reduce the reservoir pressure and vaporize the solvent to deposit the polymer. The mixing between a drive fluid and a miscible polymer slug is greater in a finger or flow channel 15 than with a smoothly advancing front. If the polymer is not soluble in the drive fluid, this mixing of drive fluid and polymer slug will cause the polymer to precipitate selectively in the finger and thereby even the flow pattern.

20 Referring now to FIGURE 2, a diagram of a producing field is shown. The shaded area A within the dashed lines is a representative portion of this field and with its injection well, I, and production well, P, is the area chosen for study in FIGURES 4 to 11. In a series of laboratory 25 studies, area A was simulated by a consolidated sandstone plate one-eighth or one-fourth inch thick by fifteen inches square. In each experiment the plate was sealed between two plates of Lucite. Inlet and outlet holes corresponding to inlet well I and production well P, were 30 provided at opposite corners of the assembly, and suitable connections permitted liquids to be forced into the sandstone plate and through the same towards the outlet connection. This assembly was supported in a horizontal plane above a light source, and a camera was positioned directly above the assembly to photograph the flow of colored fluids as they were passed from the inlet to the outlet connection. Cooled air was blown across the bottom surface of the assembly to prevent the hot light source from heating the assembly during a test run. Color 35 slides or color movies were made during the tests to evaluate the flow patterns, and the outlet flow was measured to determine the amount of oil recovered. By this method a continuous record of the flow pattern was obtained. These photographs are depicted by FIGURES 40 4 to 11 for varied flow conditions. The fluids chosen for the flow studies were diethylene glycol, isopropanol, hexane, light mineral oil, carbon tetrachloride, and solutions of polyisobutylene in hexane and carbon tetrachloride. Vertical sweep difficulties were eliminated by blending 45 the fluids to match densities and by use of thin sandstone composites, one-eighth or one-fourth inch in thickness. The above fluids were blended to obtain the desired viscosities and densities for each test run. All fluids had approximately equal permeabilities in the sandstone 50 composite. The mobility ratio between any two fluids was thus equal to their viscosity ratio. A two phase system was first studied and the results of this study are shown graphically in FIGURE 3, which is a plot of percent recovery of oil in place at breakthrough versus the 55 mobility or viscosity ratio. Also plotted in FIGURE 3 are the percent of area swept, determined by planimetering the enlarged color slides of the flow pattern at breakthrough. Breakthrough is defined as the point at which the displacing fluid phase reaches the output well or connection. Some additional recovery of oil will be achieved 60 after breakthrough by continued displacement, but the displacing fluid soon channels down the finger and no longer displaces any appreciable amount of the oil in place. Thus, breakthrough recovery data give good indications 65 as to the efficiency of the process. An inspection of FIGURE 3 shows that the area swept at any mobility ratio is greater than the percent recovery of oil in place. This is because the oil and displacing fluid mix at the interface and some of the oil in place dissolves in the miscible displacement fluid. FIGURE 3 thus gives an indication of

70 75

the amount of miscible fluid necessary to maintain separation of the drive fluid with the oil phase. At a mobility ratio of 10, the mixing zone, or difference between area covered and percent oil recovered, amounts to about 9% of the pore volume. Therefore, the miscible fluid should be employed in an amount corresponding to 9% of the reservoir pore volume in order to maintain separation of the drive fluid and the oil phase. FIGURE 3 further shows that the size of the mixing zone, or amount of oil dissolved in the displacement fluid, decreases as the mobility ratio between the fluids is decreased. The decreased volume of mixing zone with decreased mobility ratio relationship thus justifies the use of the more expensive hydrocarbons, e.g., pentane, as miscible displacement fluids. For example, under reservoir conditions, the viscosity ratio of crude oil to propane is about 16. Polyisobutylene can be dissolved in pentane to give a mobility ratio of 1 or less. The size of the mixing zones as determined by FIGURE 3 is 0.09 pore volume for propane and 0.04 pore volume for the pentane solution. Therefore, although pentane is more expensive than propane, the lesser amount of pentane than propane required for displacement will offset the higher unit cost of pentane. In addition, the oil recovery has been increased from 35% to 66.4% of oil in place. FIGURE 3 also indicates that the amount of miscible fluid employed should be greater than 0.03 pore volume and preferably greater than 0.05 pore volume to insure separation of the drive fluid and reservoir oil. Of course, it would be necessary to drive the miscible slug of pentane and polyisobutylene with a drive fluid which could be a low viscosity reservoir gas or a viscous mixed gas-water drive. If a low viscosity gas were used, the polyisobutylene could be added in decreasing concentrations as the slug-drive interface is approached to equalize the viscosities at the slug-drive interface. Such a system would have complete miscibility between the drive gas and all portions of the slug phase. A mixture of gas and aqueous polymer solution might also be employed as the drive fluid to achieve a viscous drive in combination with the viscous miscible fluid slug. Again, the isobutylene concentration may be staged between the oil interface and the drive interface to grade evenly the viscosity difference between the oil and drive phases.

The following examples will serve to illustrate the invention:

Example 1

FIGURES 4 and 5 depict the flow pattern of a run with a viscous miscible fluid slug of 10 percent of pore volume followed by a low viscosity drive. The sandstone "formation" was saturated with a simulated "oil" consisting of a mixture of diethylene glycol and isopropanol. Isopropanol was employed as the miscible displacement fluid, and a mixture of C_6 hydrocarbon was employed as the drive fluid. The miscible slug was miscible with both the "oil" and the drive fluid, but the latter was immiscible with the "oil." The viscosity ratios were:

Simulated oil to miscible fluid 11.3
Miscible fluid to drive fluid 6.63
Simulated oil to drive fluid 75.0

The flow pattern at 20 percent pore volume of fluids injected is shown in FIGURE 4. The flow pattern at breakthrough is shown in FIGURE 5. The recovered oil at breakthrough was 27.6 percent of the oil in place. FIGURE 5 shows pronounced fingering of the displacement fluid and a relatively poor areal sweep efficiency due to the high mobility ratios encountered. The final breakthrough was achieved by immiscible flow through the oil phase, represented by the dashed lines extending from the tip of the finger to the producing well. This flow was due to the drive fluid which broke through the miscible fluid slug phase and passed into the oil phase. When this happens, the drive fluid channels directly to the producing well in very thin well defined paths and efficient areal sweep is lost. This breakthrough, as well as the pro-

nounced fingering, was due to the high mobility ratios employed.

Example 2

FIGURES 6 and 7 depict another flow system with the same ratio of oil to drive fluid viscosities; however, in this test, the miscible fluid slug was gradated into three bands of successively lower viscosities from the oil interface to the drive interface. The viscosity gradients of the slug were obtained by mixing diethylene glycol with isopropanol for slug portions 1 and 2 and mixing hexane with isopropanol for slug 3. All other conditions were duplicates of those employed in Example 1. The viscosity ratios employed were:

15	Simulated oil to slug 1	3.0
	Slug 1 to slug 2	2.9
	Slug 2 to slug 3	3.0
	Slug 3 to drive fluid	2.9
	Simulated oil to drive fluid	75.0

20 The flow pattern after all three slugs had been injected is shown in FIGURE 6 at 25 percent pore volume of fluids injected. In FIGURE 7, the flow pattern is shown when breakthrough occurred. The recovered oil at breakthrough was 25.5 percent of the oil in place.

25 The high viscosity ratio of 75 between the drive fluid and the simulated oil phase is not an uncommon gas driving condition in many reservoirs. If the driving gas has a viscosity of 0.017 centipoise at reservoir conditions of 260° F. and 2100 p.s.i., the viscosity of the crude in the reservoir would only have to be 1.28 centipoises, a value often exceeded with heavy crude.

Example 3

30 To evaluate the effect of a viscous drive with a low viscosity miscible fluid slug, a test was made displacing light mineral oil from the sandstone layer with a miscible slug consisting of a mixture of hexane and carbon tetrachloride followed by a mineral oil drive. The viscosity ratios were:

40	Oil to slug	38.0
	Slug to drive	0.265
	Oil to drive	1.0

45 The oil recovery at breakthrough was 23.6 percent of the oil in place. The flow patterns at 20 percent pore volume of fluid injected and at breakthrough are shown by FIGURES 8 and 9, respectively. The recovery in this system was no better than obtained in Examples 1 and 2. FIGURES 8 and 9 show extreme fingering of the slug phase through the oil with poor areal sweep of the miscible slug. Continued displacement in this case will show a relatively high areal sweep of the drive fluid because the mobility ratio between the oil and drive is equal to 1. However, the miscible slug fingers through ahead of the 50 drive and is not retained between the drive and oil phases. This tendency, which is shown at breakthrough in the right side of FIGURE 9, is increased with continued displacement. Once the miscible slug is lost from between the immiscible oil and drive phases, substantial amounts of oil will be by-passed and left behind as residual oil in the 55 swept area, because the drive fluid usually employed is immiscible with the oil phase.

Example 4

60 65 This example demonstrates the preferred form of the invention. To evaluate the effect of a viscous miscible slug with a viscous drive, Example 3 was repeated, but polyisobutylene was added to the miscible slug in a concentration of 0.62 gram per 100 cc. of slug, so as to raise the slug viscosity to approximately that of the mineral oil. The results of this test are shown in FIGURES 10 and 11, where the areal sweep is shown at 20 percent recovery of the oil in place and at breakthrough, corresponding to 60.4 percent recovery of the oil in place. FIGURE 11 also shows that although fingering of the slug phase oc-

curred, it did not break through the oil phase until the oil recovery was almost four times greater than in Example 3.

An additional improvement of the areal sweep is shown in FIGURE 11 by the continuous band of slug which remained between the drive and the oil phases. This is important, since under reservoir conditions the drive and oil phases are immiscible with each other and must be separated by a miscible slug to assure that oil is not bypassed and left behind in the reservoir.

The above examples show that use of a viscous drive with a viscous miscible slug achieves substantial improvements over either the use of a viscous slug with a low viscosity drive or a low viscosity slug with a viscous drive. Use of a low viscosity drive with a gradated viscosity slug shows no improvement in oil recovery at breakthrough over that of a non-gradated slug, although there was a slightly better areal distribution of the gradated slug than the non-gradated. Because of this better distribution, continued displacement after breakthrough would show a greater recovery of oil in place than would continued displacement with a non-gradated slug.

Under reservoir conditions with a methane drive, the use of a miscible fluid slug made viscous by blending with crude oil or distillates poses a problem of immiscibility of the slug and drive phases. This is apparent from a study of FIGURE 12, which is a phase diagram for a methane, butane and C_7+ system. This system was worked out for a reservoir at 260° F. and under 2,000 p.s.i. The viscosity of the drive gas was 0.017 centipoise and that of the oil phase was 0.66 centipoise. The miscible fluid, butane, was divided into three slugs blended with reservoir oil to give equal viscosity ratios between each portion, from pure butane with viscosity of 0.09 centipoise at the drive interface to a viscosity of 0.34 centipoise at the oil interface. The viscosities of the slugs are shown on FIGURE 13. The compositions of the slugs necessary to provide these viscosities are shown on FIGURE 12. Slug 1, in contact with the oil, contains 69 percent oil. The next slug contains 35 percent oil, and the last miscible slug is pure butane. This pure butane slug is followed by a reservoir gas drive. During the displacement, fingering will occur, because the mobility ratios are not equal to 1, and the gas drive penetrates into the slugs of butane and oil. When the gas reaches slug 2, in a concentration greater than 29 percent, the slug and gas become immiscible and a large portion of the gas will flow directly to the producing well in very narrow channels. As a result, the efficiency of the miscible slug has been greatly reduced.

The limiting concentration of oil in butane to assure complete miscibility of the gas drive with the slug is shown by A on FIGURE 12 to be 95 percent butane and 5 percent oil. With such a low concentration of oil, no substantial increase in slug viscosity over that of butane can be obtained. This demonstrates that it is not possible to obtain a viscosity graded slug and still retain miscibility of the gas drive and all of the slug under reservoir conditions by blending oil stocks in the slug to increase the slug viscosity. Miscibility and viscosity increase can be obtained while retaining miscibility throughout the slug with a gas drive, however, by practicing this invention and adding a polymer to the miscible slug to increase its viscosity.

The examples have been given by way of illustration only and are not to be construed to limit the scope of this invention which is applicable to the use of any oil-soluble long chain polymer in an oil-miscible solution as a slug for a miscible fluid displacement method of secondary recovery.

I, therefore, particularly point out and distinctly claim as my invention:

1. In the miscible fluid displacement of oil from a subterranean reservoir penetrated by at least one injection well and at least one withdrawal well wherein a body of hydrocarbon liquid which is miscible in said reservoir with said oil is injected into said reservoir through said injec-

tion well and forced to sweep through said reservoir by the subsequent injection of a drive gas through said injection well, thereby displacing said oil from said reservoir and forcing the displaced oil from said reservoir through said withdrawal well, the improved method of obtaining a high areal sweep efficiency while retaining miscibility between said gas drive and said hydrocarbon liquid which comprises dissolving a long chain oil soluble polymer having a molecular weight of at least 10,000 in said hydrocarbon liquid and progressively decreasing the concentration of said polymer in said hydrocarbon liquid from the interface of said hydrocarbon liquid with said gas drive so as to provide a gradated viscosity of hydrocarbon-polymer solution from a maximum value at said oil interface to a minimum value at said gas drive interface.

2. The method of claim 1 which comprises: adding said polymer to said hydrocarbon liquid to increase the viscosity of said hydrocarbon liquid to a value determined by the following equation:

$$\mu_s \geq \mu_0 \frac{K_s}{K_0}$$

where μ_s , μ_0 are the absolute viscosities of the hydrocarbon-polymer solution and said oil, respectively, and K_s , K_0 are the permeabilities of said reservoir to said hydrocarbon-polymer solution and to said oil, respectively.

3. The method of claim 1 wherein said polymer is polyisobutylene, said hydrocarbon liquid comprises one or more members of the group consisting of butane, isobutane, L.P.G., and propane, with a solutizer, and said gas drive comprises one or more members chosen from the group consisting of natural gas, methane and ethane.

4. The method of recovering oil from a subterranean reservoir which comprises pressurizing said reservoir by injecting into a first well communicating with said reservoir at least 3 percent of said reservoir volume of a liquid hydrocarbon solution of an oil-soluble long chain polymer with a molecular weight greater than 10,000, thereafter injecting a drive gas into said reservoir, maintaining sufficient pressure on said reservoir to retain the injected hydrocarbon in liquid phase within said reservoir by controlled withdrawal of displaced oil from said reservoir through a second well communicating with said reservoir, detecting the proximity of said liquid hydrocarbon to said second well, reducing the pressure on said reservoir when said liquid hydrocarbon-polymer solution reaches said second well, withdrawing vaporized hydrocarbon, repeating said pressurization by repeated injection of said liquid hydrocarbon solution of said polymer followed by repeated injection of said gas drive, recovering additional displaced reservoir oil, and repeating said depressurization of said reservoir when said liquid hydrocarbon solution of said polymer again reaches said second well, continuing said repetition of the pressurization and depressurization steps until said reservoir is substantially swept free of all oil in place.

5. The method of recovering oil from a subterranean reservoir which comprises pressurizing said reservoir by injecting a liquid hydrocarbon solution of an oil-soluble long chain polymer having a molecular weight greater than about 10,000 into said reservoir through a first well communicating with said reservoir, forcing said liquid hydrocarbon solution through said reservoir by the subsequent injection of a drive gas into said first well, maintaining sufficient pressure on said reservoir to retain the injected hydrocarbon in liquid phase within said reservoir by the controlled withdrawal of displaced oil from said reservoir through a second well communicating with said reservoir until said liquid hydrocarbon solution reaches said second well, thereafter reducing the pressure on said reservoir to below the vapor pressure of said liquid hydrocarbon within said reservoir to thereby vaporize said liquid hydrocarbon and deposit said dissolved polymer within the flow channels of said reservoir, withdrawing vaporized hydrocarbon, repeating said pressurization by repeated injec-

tion of said liquid hydrocarbon solution of said polymer followed by repeated injection of said gas drive, recovering additional displaced reservoir oil, repeating said depressurization of said reservoir when said liquid hydrocarbon solution again reaches said second well, continuing said repetition of the pressurization and depressurization steps until said reservoir is substantially swept free of oil.
